UNITED STATES PATENT OFFICE

2,170,224

UPHOLSTERED FURNITURE

Samuel Tarr, Chicago, Ill.

Application May 16, 1936, Serial No. 80,025

4 Claims. (Cl. 155—182)

This invention relates to upholstered furniture, such as sofas, chairs, settees and the like, and relates particularly to an upholstered article of furniture which is provided with an upholstery covering which can be readily removed and replaced. By the term upholstery covering I desire to clearly differentiate from the so-called slip covers which are applied over upholstered articles of furniture on top of the upholstery covering proper. My upholstery covering further differentiates from the conventional slip covers in that it is mounted on the article of furniture in a manner which is indistinguishable in appearance from a covering permanently applied in the usual way, that is, by being tacked in position.

In producing an upholstered article of furniture having a real upholstery covering, which is nevertheless removable and replaceable with facility, several problems are presented which are solved by the present invention. In the first place, a simple and effective attachment must be provided for an edge of covering fabric which may terminate in full view at a piece of wood trim. Furthermore, the covering must be held closely to the frame or to elements carried thereby at certain definite places. Thus, in a case of overstuffed furniture with rolled arms, the fabric must be held close to the underside of the arm where the fabric turns sharply downward. Then, again, to present a proper appearance the panel in front of the seat of a chair or couch must be anchored to the seat in order to present a finished and high-class appearance. The same is true for the flat portion of the fabric which extends from the front top edge of the seat rearwardly. Ordinarily, the tapestry or patterned material terminates a few inches from the top front edge of the seat and is there secured to other material. The line of join between the two materials is firmly anchored to the spring structure of the seat in ordinary high-class furniture. My invention is primarily concerned with means for attachment at the points indicated, whereby I am enabled to provide an upholstery covering which is readily removable and replaceable and which nevertheless has all the qualities of excellent fit and finished appearance of a covering which has been permanently attached by a competent upholsterer.

The invention will readily be understood from the following description of a preferred embodiment thereof, taken in conjunction with the accompanying drawings in which:

Figure 1 is a perspective view of a couch embodying my invention;

Fig. 2 is a transverse sectional view therethrough, taken on the line 2—2 of Fig. 1;

Fig. 3 is an inverted view of the couch, showing the bottom panel thereof;

Fig. 4 is a fragmentary view showing a rear corner of the couch with the upholstery covering partially broken away;

Fig. 5 is a fragmentary sectional view through the arm of the couch, this view being taken on the line 5—5 of Fig. 2;

Fig. 6 is a perspective view showing the manner in which the upholstery covering of a cushion is removably installed;

Fig. 7 is an elevational view showing the manner in which the edge of an upholstery covering is removably secured to wood trim, this figure showing the application thereof to the back of a couch having a curved corner;

Fig. 8 is a similar view showing the manner in which this feature of the invention is applied to a piece of wood trim having a rectangular corner;

Fig. 9 is a sectional view, taken on the line 9—9 of Fig. 7, this view being on a substantially larger scale;

Fig. 10 is a sectional detail view, taken on the line 10—10 of Fig. 8, likewise on a larger scale;

Fig. 11 is a fragmentary sectional plan view, taken on the line 11—11 of Fig. 2, the cushion and upholstery covering being removed;

Fig. 12 is a perspective view of a tube element adapted to be mounted in a groove on wood trim, as will hereinafter be described;

Fig. 13 is a complementary tube element adapted to be secured to the upholstery covering;

Fig. 14 is a perspective view of a flexible rod which may be used in the securing of the upholstery covering to the article of furniture;

Fig. 15 is a fragmentary perspective view of a tubular element employed in my invention;

Fig. 16 is a diagrammatic view showing this tube member and complementary tube elements on fabric about to be installed;

Fig. 17 is a detail view showing the manner in which certain parts of the upholstery covering are provided with eyelets;

Fig. 18 is a sectional detail view showing the manner in which said eyelets are connected to a turn-button for the installation of certain parts of the upholstery covering;

Fig. 19 is a sectional view showing a further embodiment of attaching means which may be employed according to my invention;

Fig. 20 is a similar view showing a still further form of attachment which may be employed according to my invention, and

Fig. 21 is a fragmentary sectional detail.

Referring to the drawings, the reference numeral 21 designates the article of furniture as a whole. This article of furniture is shown in the form of a couch of conventional design. It will be understood, however, that any other upholstered article of furniture may be equipped with the present invention and that the invention is

not in any respect limited to the particular design of the couch shown. The couch 21 comprises a spring seat portion 22, back 23, ends or arms 24 which terminate in rolls 25 at their upper ends. 5 The couch is supported on legs 26 which are secured to the rigid frame of the couch in suitable manner. The couch, as a whole, is upholstered in the usual manner and is provided in the manner usual with high-class furniture with inner coverings 27 which may suitably be of stout cotton fabric of white or natural color. The coverings 27 are permanently secured to the frame members of the couch by tacks 28 as is conventional in upholstery. The underside of the 10 couch; that is, below the spring structure 22, is closed by a sheet of fabric 29. To the sheet of fabric 29 is secured a panel 30 of suitable fabric which is somewhat smaller than the dimensions of the underside of the couch, as is shown in Fig. 3. The sheet 29 and panel 30 are secured together by stitching 31 at some distance from the edges of the panel 30. The edges of the panel 30 are provided with slide fastener or zipper elements 32 which are intended to cooperate with complementary elements 33 on the edges of the 15 upholstery covering. It will readily be understood that when the slide fastener elements 32 and 33 are brought into registration, as shown in Fig. 3, the elements may be interlocked by 20 suitable operation of the conventional slides 34.

The upholstery covering is preferably formed of one piece, although in the case of the embodiment of the invention illustrated where the upper edge of the back of the couch is constituted by a piece of wood trim 35, the back upholstery panel 36 may be separate from the rest of the upholstery covering and it may be tacked, or otherwise permanently secured to the back at its upper end, as shown in Fig. 2. It will be understood that the invention is not intended to 25 be limited in this respect since the panel 36 may be secured to the wood trim 35 in the same way as the front panel 37 of the couch back is secured thereto. At any rate, the lower part of the panel 36 must be capable of being freed so as to render 30 it possible to make suitable manipulations in the opening 38 between the back and seat of the couch, as shown in Fig. 2.

As shown in Fig. 2, the seat portion 22 of the couch is provided with a rear frame member 39. Upon this rear frame member is mounted a suitable number of turn-buttons 40 of well known type, as shown in Fig. 18. The panel 41 which rests upon the seat of the couch is provided along its rear edge with suitable eyelets 41a located in registry with the turn-buttons 40, Fig. 2. The ends of the panel 41 are also provided with eyelets 41a which are in registry with turn-buttons 42, Fig. 5, located along the upper edge of the frame members 43 which also form part of the seat. It will be noted that there is an opening 44 between the arm structure and the seat structure so that the fabric 27 can be moved into the position shown in Fig. 5. The fabric 41 which forms the inner sides of the coverings for the arms is also provided at its lower edge with eyelets which register with the turn-buttons 42. When the covering is installed, the fabric 45 overlies the fabric 41 at these turn-buttons. Referring again to the turn-buttons 40, it will be noted that the fabric 37 which forms the front side of the back 23 of the couch, is also formed with eyelets which are engaged by the turn-buttons 40.

75 The fabric 45 extends around the roll 25 of

the arm. It is rigidly and detachably secured at the underside of the roll 25 by the wire 46, as will hereinafter be described. From the wire 46 the fabric 45 covering the arm extends downwardly and turns under the bottom of the couch, 5 this fabric carrying slide fastener elements 33 as shown in Fig. 3. The fabric 45 is preferably in the form of a pocket which is closed by a front panel 47, as shown in Fig. 1. A space 48 is provided between the back 23 of the couch and 10 each end frame member 49, as shown in Fig. 4. This end frame member 49 carries turn-buttons 50, to which may be secured parts of the ends of the panel 37 and also the rear edges of the portion of the fabric 45 on the inner side of the 15 arms 24.

It will be understood that the front panel of the seat 51 which is secured to the panel 41 adjacent the wire 52, extends downwardly over the front of the seat and turns inwardly and rearwardly therebeneath. Along its lower edge it carries slide fastening elements 33, as shown in Fig. 3. The lower end of the panels 36 turns forwardly underneath the seat 22 of the couch and is provided at its extremity with slide fasteners 33, as shown in Fig. 3.

As has been heretofore indicated, it is necessary for upholstery having a proper finished appearance to have the covering attached to the seat structure at the position of the wire 52 and preferably also at a position more to the front of the panel 51, that is, at the position of the wire 53 as shown in Fig. 2. This attachment is preferably attained in detachable manner by means of the cooperating tubular elements illustrated in Figs. 13 to 16 inclusive.

I provide a principal tubular member 54 which is rigidly secured to the spring structure of the seat 22, for example, by means of wires 55 at the particular positions of the wires 52 or 53, 40 shown in Fig. 2. The tubular member 54 may be bent to conform to the particular configuration required by the contour of the article of furniture. It is provided along its length with a series of cut-outs 56, as best shown in Figs. 15 and 16. 45 These cut-outs are adapted to receive correspondingly spaced tubular elements 57 which are fastened to the fabric. The tubular elements 57 have soldered or otherwise rigidly secured thereto staples 58 of flat stock. To secure them to the fabric of the upholstery covering it is merely necessary to project the sharp ends of the staples 58 through the fabric and then to bend them over, as is shown in Fig. 16. When the tubular members 54 and 57 are in cooperative 50 relation, the appropriate rod 52 or 53 is passed therethrough and in the final assembly the rods 52 and 53 occupy the position shown in Fig. 2. It may here be noted that in the case of a chair, one rod 52 and one rod 53 may be employed. 55 In the case, however, of a longer piece of furniture, such as a sofa, it is preferred to introduce rods 52 and 53 from opposite ends of the article of furniture. This introduction is effected through suitable openings in the arms 24, which 60 openings 44, Fig. 5 are hidden when the assembly is completed by the panels 45. I prefer to make the tubular members 54 and 57 from metal pipe. However, these tubular elements may be formed of any suitable material, for example of leather, 65 woven fabric or the like, and it is not intended to limit the structure to tubular elements of metal, because rigid non-metallic material may also be used if desired.

A somewhat similar arrangement is employed 75

for the connection of the material of the upholstery covering to wood trim. In this case I prefer to form in the wood trim a groove 59 and in this groove are located tubular elements 60 of the type shown in Fig. 12. These tubular elements are again preferably of metal and have soldered or otherwise secured thereto sharp points 61. As indicated in Fig. 12, these sharp points may be provided by soldering tacks to one side of the tubular member 60. The edge of the fabric which is to be secured to the strip 35, for example, is provided with tubular elements 57 of the type previously described, which tubular elements are spaced in complementary relation to the tubular elements 60. This relationship is best shown in Fig. 7. The elements 57 and 60 are held in assembled relation by means of a rod 62, as shown in Fig. 9. It will, of course, be understood that the prongs of the staple 58 which extend 20 through the fabric are masked in any suitable way, for example, by means of a tape or length of guimpe 63, as shown in Fig. 7. Instead of the tape 63, any suitable fringe may be employed, if desired. It will be understood that the rod 62 is hidden from view when the upholstery covering is completely installed. In Fig. 7 I have shown the manner of attachment to a piece of wood of arcuate design. In the case of a rectangular corner, two wires 62 are necessary, as shown in Fig. 8.

It will be understood that the wire 46 previously referred to is mounted with the aid of a tubular member 54 and tubular members 57 through which the wire 46 extends. The tubular member 54 at this location is secured to the arm frame by wires 64, as shown in Fig. 5. It will also be understood that this manner of attachment may be employed at any place where fashion requires the fabric of the upholstery covering to be anchored to the frame or elements supported thereby.

In the embodiment of the invention illustrated, the panel 51 is permanently united to the panel 41. At opposite ends the panel 51 is permanently secured to the panel 47 and thereby to the fabric 45. The fabric 45 may be secured to the fabric 37 adjacent the upper sides of the arms. Below this point these fabrics are separate, in order to permit them to be attached separately to the turn-buttons 50 as previously described. If the back panel 36 is permanently mounted as illustrated, although it may be removably secured to the wood trim 35 like the panel 37, then the fabric 45 on the outside of the arms may extend rearwardly around a corner of the article of furniture and be secured to the panel 36. It is preferred to secure the meeting edges by providing them with slide fastener elements 65, as shown in Fig. 4. These slide fastener elements 65 not only 60 secure the attachment of the outer covering of the arms 24, but they provide an easy means for making available the turn-button 50.

In the case of a rather extensive leg, such as the front legs 26 shown at each end of the couch, it may in some cases be necessary to provide some anchorage for the lower edge of the fabric. Thus, I may mount on the frame buttons 66 by means of pins 67 as shown in Fig. 21, which buttons extend through suitable openings in the appropriate fabric. Of course, other means of securing at this point may be employed, for example the well known snap fasteners, which have the advantage of holding the fabric in position and at the same time are concealed from view by the fabric.

The invention will be more completely understood from the following description of the manner in which the removable covering is applied to the article of furniture illustrated. The wires 52 and 53 are first installed, the covering as a whole being practically turned inside out and located in front of the couch. The pipe elements 57 on the covering are brought seriatim into the openings 56 in the tubular structures 54 and the wire 52 or 53, as the case may be, is pushed inwardly step by step from one end of the couch. It will be understood that the arm structure 24 is provided with suitable openings to permit the wires to be fed therethrough. The upholstery covering is then straightened out, the panel 51 being hung downwardly in front of the seat and the panel 41 being spread over the surface of the seat.

The portions of the covering including the panels 45 and 47, by means of which the arms are enclosed, are slipped over the arms and the panel 37 is spread over the back. In case the back panel 36 is integral with the front panel 37, as is the case with articles of upholstery not provided with wood trim 35 at the top of the back, 25 the back covering is worked over the back structure 23. The wires 46 are installed, suitably from the rear. The ends of the panel 41 are extended into the openings 44 and the eyelets at these ends are slipped over the turn-button 42. The 30 lower sides of the panel 45 are likewise slipped into the openings 44 and the eyelets at their extremities are slipped over the turn-buttons 42. These turn-buttons are then turned to anchor firmly these panels in place. Then the rear portion of the panel 41 is worked rearwardly into the opening 38 and the eyelets therein are passed over the turn-buttons 40. The lower end of the panel 37 is likewise worked into the opening 38 and its eyelets are passed over the turn-buttons 40. These turn-buttons are then turned so as 45 to anchor these panels firmly in place. The rear edge of the portions of the panels 45 on the inside of the arms is worked back into the opening 48 and the eyelets therein are passed over the turn-buttons 50. Then the free edge portions at each side of the panel 37 are moved into the openings 48 and their eyelets are passed over the turn-buttons 50. These turn-buttons are then turned so as to secure these panels firmly in position. 50

It will readily be understood that the openings 38, 44 and 48 are available from the outside of the upholstered article because the exterior panels are not anchored to the bottom. Before this is done, the upper edge of the front panel 37 of 55 the back of the upholstered article must be secured to the wood trim 35, where such trim is used. For this purpose the wire 62 is passed upwardly through a channel in the wood trim, as shown in Fig. 9, and is passed through the tubular portions 57 and 60, shown in Fig. 7. A wire 62 is fed in from each end and is continued until the upper edge of the panel 37 is firmly secured in place. After the wires 62 have been installed, the ends are secured in any suitable way, but are 65 in any event hidden from view by the exterior panels.

In the modification shown, the front panel 51 is smoothed down over the front of the seat 22 and turned inwardly underneath. The lower edge 70 of this panel is secured to the panel 30 by means of the slide fastener elements 32 and 33, as shown in Fig. 3. The end panels 45 are likewise smoothed down and turned inwardly below the bottom of the upholstered article and are united 75

to the panel 30 by means of the slide fastener elements 32 and 33, as shown in Fig. 3. Likewise, the rear panel 36 is smoothed down and connected in the same manner to the panel 30. In 5 the particular case illustrated, where the back panel 36 is not made removable, the slide fastener elements 65 are operated so as to connect this rear panel to the side panels 45. Any supplementary fastenings, such as the buttons 66 shown 10 provided adjacent the legs 26, are secured in place and the installation is complete. To remove and replace the upholstery covering described is a matter of a few minutes' work. In case the upholstery covering has become soiled it may be 15 readily removed, cleaned and replaced. In the case of hotels where a large number of similar upholstered articles are provided, the upholstery covering may be removed and replaced by another of different color or different fabric, to suit a new 20 scheme of decoration or to please the taste of a guest.

The cushions employed in upholstered articles equipped with my invention may suitably comprise pillows 68 which are enclosed within a 25 cushion cover 69 of conventional type except that it can readily be opened along one edge. As shown in Fig. 6, I may provide a meeting edge with snap fasteners 70 so as to provide a movable flap for the removal and replacement of the pillow 68.

30 It will readily be understood that considerable modification may be made in the application of my invention to upholstered articles. In particular, the tubular structures 56 and 57 may be modified in various ways. In Figs. 19 and 20 35 I have shown two embodiments of a securing structure which has certain advantages over that employing the tubular member 54. Referring to Fig. 19, it will be seen that I provide alternate tubular members 71 and 72. The tubular members 71 are secured by wires 73 to the 40 spring structure of the upholstered article or to a rigid part of the frame thereof. The other tubular portions 72 are secured to fabric 74 of the upholstery covering by means of staples 75.

45 The tubular members 72 are provided with pivotally mounted latches 76 which are pressed outwardly from each end by means of a spring 77. A lateral opening 78 permits the spring 77 to be moved to retract these latches. When it is desired to secure the fabric 74 in position the tubular elements 72 are merely pushed inwardly between two adjacent tubular elements 71. The latches 76 snap into the tubes 71 and engage 50 projections 79 therein. When it is desired to remove the covering, a suitable tool is introduced into the opening 78 and the spring 77 is manipulated so as to draw the latches 76 together. When these latches clear the projections 79, the tubular member 72 may be moved out of position.

60 In the modification shown in Fig. 20, tubular members 80 are permanently secured to the upholstered article and the tubular elements 81 are secured to the fabric. At one end each tubular element 81 is provided with a reduced extension 65 82 which extends into one end of the tubular member 80. The tubular member 80 carries a plunger 83 which is normally spring pressed so as to extend outwardly from its other end by means of a spring 84. The plunger 83 is provided on one side with a pin 85 which projects 70 outwardly through a slot 86. The spring 84 may suitably abut against an inturned lug 87 stamped out of the metal of which the tube 80 is formed.

In the operation of this embodiment the tubular element 81 is manipulated so as to direct its projection 82 into the appropriate tubular member 80. Then the plunger 83 of the tubular member 80 located at the other end of the tubular member 81 is retracted and the adjacent ends of the last mentioned tubular elements are brought into alignment. Then the plunger 83 is released and allowed to enter the tubular element 81. The structures shown in Figs. 19 and 20 provide a greater degree of resilience than can be attained by a structure comprising an integral tubular member 54 of considerable length.

Although the invention has been disclosed in connection with the specific details of preferred embodiments thereof, it must be understood that such details are not intended to be limitative of the invention except in so far as set forth in the accompanying claims.

Having thus described my invention, what I claim as new and desire to secure by Letters Patent of the United States is:

1. In a readily removable upholstery covering structure, in combination, a piece of wood trim 25 provided with a groove, rigid tubular members mounted in said groove and rigid tubular members mounted on said covering adapted to be placed within said groove in abutting and alternating relation with said rigid tubular members mounted therein, and an elongated member extending through said tubular members in series whereby the covering is secured to the wood trim.

2. In an upholstered article of furniture, having a removable cover simulating a covering 35 which is permanently installed, in combination, rigid tubular members on said covering, rigid tubular members on the article, the rigid tubular members on the covering and article respectively being arranged in alternating and abutting 40 relation, means securing the adjacent tubular members together whereby the covering is securely and removably anchored to the article, and means carried by the covering adapted to overlie the tubular members.

3. In an upholstered article of furniture, having an upholstered seat and a removable cover simulating a covering which is permanently installed, said cover extending around the front corner of the seat, in combination, a series of 50 rigid tubular members in spaced relation mounted on said article of furniture along said seat and adjacent said corner, complementary rigid tubular members on said cover, the rigid tubular members on the article and cover respectively 55 being arranged in alternating and abutting relation, and a wire extending through the tubular members, whereby the covering is securely and removably anchored to the article adjacent the front corner of the seat.

4. In an upholstered article of furniture, having a removable cover simulating a covering which is permanently installed, in combination, rigid tubular members on said covering, rigid tubular members on the article, the rigid tubular members on the covering and the article respectively being arranged in alternating and abutting 65 relation, a long flexible wire extending through said tubular members whereby the covering is securely and removably anchored to the article, and means carried by the covering adapted to overlie the tubular members.

SAMUEL TARR.
